No. 838,460.

PATENTED DEC. 11, 1906.

S. S. SADORUS.
ROTARY ENGINE.

APPLICATION FILED MAY 16, 1906.

UNITED STATES PATENT OFFICE.

SAMUEL S. SADORUS, OF SARILDA, IDAHO.

ROTARY ENGINE.

No. 838,460.

Specification of Letters Patent.

Patented Dec. 11, 1906.

Application filed May 16, 1906. Serial No. 317,133.

To all whom it may concern:

Be it known that I, SAMUEL S. SADORUS, a citizen of the United States, and a resident of Sarilda, in the county of Fremont and 5 State of Idaho, have invented certain new and useful Improvements in Rotary Engines, of which the following is a specification.

My invention is an improvement in rotary engines; and it consists in certain novel 10 constructions and combinations of parts, as will be hereinafter described and claimed.

In the drawings, Figure 1 is a transverse section on about line 1 1 of Fig. 2. Fig. 2 is a cross-section on about line 2 2 of Fig. 1. 15 Fig. 3 is a sectional perspective view illustrating the packing-strips secured within the rim of the casing. Fig. 4 is a sectional perspective view illustrating the packing-strips secured within the rim of the revolving piston. 20 Fig. 5 is a cross-sectional view; and Fig. 6 is a face view, partly in section, of one of the piston-blades. Fig. 7 is a detail plan view of one of the abutments with the side plates thereof in place.

25 In carrying out my invention the casing A has inlet-ports B and b, supplied from the pipe C, the latter having a branch C', leading to the port b, and the casing also has the exhaust-ports B' and b', the steam supplied 30 through the ports B and b exhausting through the ports B' and b'. The casing comprises the side plates A' and A² and the rim A³, the head D operating within the casing and being suitably secured to a shaft E, whereby to 35 operate the same. This piston D is provided at its opposite sides with the outwardly-projecting flanges D', projecting beyond its rim-plate D² and forming a circumferential channel in the outer edge of the piston, in which 40 operate the blades of the piston and the abutments of the casing, as will be understood from Fig. 1. The abutments a project inwardly over the rim of the casing and are of a width to fit snugly between the flanges 45 D' of the piston-head and are preferably provided at their opposite sides with the spring packing-plates a', secured at a² by bolts, or otherwise, to the opposite sides of the abutment a and flaring slightly toward their 50 opposite ends and provided at their opposite or free ends with inwardly-projecting flanges a³, which lap along the square face a⁴ of the abutment, the opposite or rear face a⁵ of the abutment being sloped, as shown in Figs. 1 and 3, to properly depress the piston-blades 55 in the operation of the engine.

The engine is packed between the outer edges of the flanges D' and the inner face of the rim A³ of the casing. This is preferably accomplished by means of packing-strips 60 seated in suitable grooves, as shown in Figs. 3 and 4.

In Fig. 3 the packing-strips F are seated in grooves f in the inner face of the rim A³ at points opposite the edges of the flanges D', 65 while in Fig. 4 the packing-strips F' are seated in grooves f' in the edges of the flanges D'. In both instances the packing-strips are reduced and overlap at their ends to form a complete joint. These packing-strips may 70 be of any suitable metal and will operate to secure a tight joint as desired. The outer surface of the rim D² of the piston D moves in close proximity to the inner edges of the abutments a, and the piston-blades G are pivoted 75 to the piston, and preferably in the inner faces of the flanges D' thereof, by means of pivoted stops G' on the blades entering sockets d' in the inner faces of the flanges, as shown in Fig. 4. The blades are so arranged 80 that when closed they will be seated in recesses d² in the outer face of the rim D², as in passing the abutments and when so seated they will compress the springs d³, which are preferably spring-plates secured at one end to 85 the piston adjacent to the pivot of the blades G, and deflected outward toward their other or free ends, so that after the blades have passed the abutments the springs d³ will tend 90 to throw the said blades slightly outward, so they can be acted upon by the steam fed into the casing. The piston-blades G are provided in their outer edges with packing-strips in the form of rollers G², which bear against the inner face of the rim A³ of the casing. The 95 packing-rollers G² are pressed outwardly by means of springs G³ bearing against blocks G⁴, in which the rollers bear at their inner sides, as best shown in Figs. 5 and 6 of the drawings. When the pistons are thrown out 100 to operative position, as shown in Figs. 1 and 4, they abut against the free ends of side springs H, the said side springs being fitted against the inner faces of the flanges D' of the piston, secured by rivets or otherwise at one 105 end H' to the sides of the casing and preferably recessed therein, as best shown in Fig. 4, and extending at their other ends laterally into the annular recess in the outer face of the piston with their free ends h deflected 110 outwardly, so they may form stops for the blades G when the latter are in operative po-

sition, and yet can move past the abutments *a* as the piston revolves in the casing.

It will be noticed that in operation when the packing-strips shown in Fig. 3 are employed they are constructed to have contracting action upon the free edges of the flanges *D'* of the piston, while the form of packing-strip shown in Fig. 4 is designed to operate with an expanding action to press against the inner face of the rim *A'*, the construction in both instances operating to prevent the waste of steam laterally between the flanges of the piston and the casing.

I claim—

- 15 1. The improvement in rotary engines herein described comprising a casing having its rim provided with inwardly-projecting abutments, spring-plates at the opposite sides of the abutments and flaring toward their free ends, a piston-head having a rim and flanges projecting outwardly beyond the same, the rim being provided with recesses for the blades and with springs therein for giving the blades their initial opening movements, the piston-blades pivoted at their inner edges within the rim-recesses and adapted to seat in said recesses in passing the abutments of the casing, said blades being provided in their outer edges with the packing-rollers and with springs for actuating the same, the side plates secured to the inner faces of the piston-flanges and springing at their free edges inwardly to position for abutment by the blades when the latter are opened, and packing-strips between the flanges of the piston and the rim of the casing, substantially as set forth.
- 20 2. In a rotary engine the combination of a piston and a casing having abutments and provided on the opposite sides of the abutments with plates springing outwardly at their free edges to form a close joint with the piston, the piston having portions operating alongside the said plates, substantially as set forth.
- 25 3. The combination in a rotary engine with the piston and the casing, of the blades

pivoted to the piston and abutments projecting from the casing in the paths of said blades and provided on their opposite sides with spring-plates, the piston having opposite outwardly-projecting flanges operating along the outer sides of the said spring-plates, substantially as described.

4. The combination with the casing and the abutments, of the piston having the pivoted blades and the spring-plates secured at one end beneath the blade adjacent to the pivot thereof and deflected outwardly toward their free ends and arranged at said ends beneath the free edge of the blade for initially opening the same, substantially as set forth.

5. The combination with the piston, of the side flanges, the pivoted blade and the side plates secured to the said flanges and projecting at their free edges to form a stop for the blade, substantially as set forth.

6. The combination in a rotary engine of the casing, the abutment, the piston having the side flanges and the blade operating between the same, and the spring-plates secured to the inner faces of the side flanges, substantially as set forth.

7. The combination in a rotary engine of the casing having the abutment provided with springs at its opposite sides, the piston having the side flanges and the blade, and the side plates secured to the inner faces of the piston-flanges, substantially as set forth.

8. The combination with the piston-rim recessed for the blade and the side flanges provided in their inner faces with sockets opposite the said recess, of the side plates secured to the flanges and projecting at their free edges to form stops for the blade, the piston-blade having the pivot-studs journaled in the sockets of the side flanges, and means for spring-actuating said blade, substantially as set forth.

SAMUEL S. SADORUS.
